CLAIM

The ornamental design for an apparatus to control fluid flow
through a tube, as shown and described.

DESCRIPTION

FIG. 1 is a front, bottom, and right side perspective view of the
apparatus to control fluid flow through a tube, showing my
new design;

FIG. 2 is a back, bottom, and left side perspective view
thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, bottom, and right side perspective view
showing the door open thereof.

The broken lines in the drawings represent an environmental
subject matter and form no part of the claimed design.
